OPAQUE AQUEOUS POLYVINYL PYRROLIDONE HAIR SETTING COMPOSITION

Albert Shansky, Norwalk, Conn., assignor to Turner Hall Corporation, New York, N.Y., a corporation of New York
No Drawing. Filed Aug. 15, 1963, Ser. No. 302,450
4 Claims. (Cl. 167—87.1)

The present invention relates to compositions for setting hair on the human head, and more particularly to an improved setting solution.

In dressing a woman's hair, customarily an altered wave shape is imparted to the hair strands so as to maintain some desired selected hair style. Such alteration may be permanent as in cold permanent waving or temporary, i.e., transient, as in setting.

Hair setting lotions are usually comprised of aqueous or hydro-alcoholic solutions of polymeric materials. Said polymeric materials by reason of their large molecular size form films on the hair strands after drying. In some cases the materials may penetrate the hair and form internal deposits in addition to outer films. Such films and deposits have a stiffening action which tends to hold the hair in place temporarily.

Conventionally, materials of a resinous nature are employed in setting solutions, polyvinyl pyrrolidone being one of the most widely used of such materials. A process and composition for temporarily setting hair with this substance is set forth in United States Patent No. 2,793,980.

Polyvinyl pyrrolidone setting solutions have, conventionally, been clear. This has been so despite the fact that from an esthetic point of view it would be desirable for the setting solutions to be opaque since the public and beauty trade regard opacity as good for the hair and as an indication of softness and mildness and, conversely, believe that clear solutions dry out the hair and are bad for it.

Despite the need for an opaque polyvinyl pyrrolidone setting solution, none has previously been made. One reason is that PVP is not compatible with conventional resinous oil-emulsion opacifiers such as urea formaldehyde resins, melamine formaldehyde resins, and abietic acid resins. Also, the over plasticizing (softening) action inherent in such opacifiers adversely affects the film forming properties of the polyvinyl pyrrolidone, to the detriment of the setting solution functionally.

It is a principal object of the present invention to provide an opaque PVP setting solution having setting abilities at least equal to those of conventional clear polyvinyl pyrrolidone setting solutions.

It is another object of the present invention to provide a solution of the character described having setting abilities superior to those of conventional polyvinyl pyrrolidone setting solutions.

It is another object of the present invention to provide a solution of the character described which is inexpensive and simple to manufacture.

Other objects of the invention in part will be obvious and in part will be pointed out hereinafter.

The invention accordingly consists of the compositions of matter hereinafter described and of which the scope of application will be indicated in the appended claims.

Pursuant to the instant invention, a specifically selected opacifying agent is employed to produce an opaque condition in polyvinyl pyrrolidone setting solutions. Said agent constitutes a primary amide produced by the reaction of ammonia and a saturated higher fatty acid the carbon chain of which has a length of from 14 to 22

2

carbon atoms and includes an even number of carbon atoms. A primary amide is an amide with an amino group attached directly to the carbon atom of the carbonyl group. It has the structural formula:

The reaction of ammonia and the fatty acid is generally as follows:

where R is a fatty acid chain.

The following is a list of amides usable pursuant to the instant invention:

Behenamide (docosanamide)— $\text{CH}_3(\text{CH}_2)_{20}\text{CONH}_2$
Arachidamide (eicosanamide)— $\text{CH}_3(\text{CH}_2)_{18}\text{CONH}_2$
Stearamide (octadecanamide)— $\text{CH}_3(\text{CH}_2)_{16}\text{CONH}_2$
Palmitamide (hexadecanamide)— $\text{CH}_3(\text{CH}_2)_{14}\text{CONH}_2$
Myristamide (tetradecanamide)— $\text{CH}_3(\text{CH}_2)_{12}\text{CONH}_2$

It has been found pursuant to the present invention that 0.1% to 1.0% by weight of the amide in the PVP solution gives a range of opacity coming within the desires of the beauty trade.

The amides employed pursuant to the instant invention are relatively insoluble in most conventional solvents including those used in polyvinyl pyrrolidone formulations. Accordingly, stock solutions of the amides in a suitable solvent are first prepared and suitable amounts of the stock solutions are incorporated in the basic polyvinyl pyrrolidone solution. An excellent solvent for the amides involved herein is Igepal CO-430 sold by the Antara Division of the General Aniline and Film Corporation, 435 Hudson Street, New York, New York. This solvent is nonylphenoxy poly(ethyleneoxy)-ethanol which is a 100% active non-ionic oil-soluble surface active agent made with four moles of ethylene oxide.

10% stock solutions of the amides usable pursuant hereto are prepared with Igepal CO-430 as the solvent. These range from clear to hazy solutions in appearance. Aliquot portions of a stock solution ranging from 1 to 10% by weight of the basic PVP solution are added to the polyvinyl pyrrolidone formulations until the desired degree of opacity is obtained.

The opacifying agents disclosed herein impart opacity to the final product in the following manner. The PVP solution is itself an aqueous one. When the amide solution is added to the basic polyvinyl pyrrolidone solution, the amide is insolubilized from the Igepal CO-430 due to the presence of an aqueous phase. The amide becomes dispersed in the aqueous phase, and it is held in stable dispersion therein by the surface activity of the Igepal CO-430 in the system.

55 Examples of stock solutions of the amides usable pursuant to the instant invention are set forth below.

Example I

	Grams
Stearamide	10
Igepal CO-430	90

Example II

Behenamide	10
Igepal CO-430	90

Example III

Palmitamide	10
Igepal CO-430	90

Example IV

Arachidamide	10
Igepal CO-430	90

Example V

Myristamide	10
Igepal CO-430	90

In making the stock solution, the materials are heated to 80° C. to solubilize the amide. The solution is cooled prior to incorporation into the basic polyvinyl pyrrolidone solution.

Examples of opaque polyvinyl pyrrolidone hair setting solutions embodying the present invention are set forth below.

Example VI

	Grams
Polyvinyl pyrrolidone	2.50
Urea	1.25
Triethanolamine	1.25
Water	85.00
10% by weight stearamide in Igepal CO-430	10.00

This solution gives a turbidity of 20% transmission with water as the reference, using a 520.mu filter in a Brociner-mass spectrophotometer.

The above example has the maximum opacity desirable. An example of a solution having the minimum opacity desirable would be as follows:

Example VII

	Grams
Polyvinyl pyrrolidone	2.50
Urea	1.25
Triethanolamine	1.25
Water	94.00
10% by weight stearamide in Igepal CO-430	1.00

This solution gives a turbidity of 60% transmission with water as the reference, using a 520.mu filter in a Brociner-mass spectrophotometer.

The optimum opacity is somewhat less than the maximum and can best be determined by trial. An example of a solution having a preferred opacity is as follows:

Example VIII

	Grams
Polyvinyl pyrrolidone	2.50
Urea	1.25
Triethanolamine	1.25
Water	88.00
10% by weight stearamide in Igepal CO-430	7.00

This solution gives a turbidity of 28% transmission with water as the reference, using a 520 mu filter in a Brociner-mass spectrophotometer.

Examples VI, VII and VIII are typical and hold true for the other primary amides listed as usable pursuant to the instant invention.

The solutions embodying the present invention are applied in the conventional manner as by spraying on the hair or combing into the hair. They exhibit a creamy or milky appearance, but their setting functions have not been impaired. Indeed, it has been found that the amides have a hair conditioning property which causes solutions embodying the instant invention to be superior functionally to conventional polyvinyl pyrrolidone setting solutions.

It thus will be seen that there are provided compositions of matter which achieve the several objects of the

invention and are well adapted to meet the conditions of practical use.

As various possible embodiments might be made of the above invention and as various changes might be made in the embodiments above set forth, it is to be understood that all matter hereinabove described is to be interpreted as illustrative and not in a limiting sense.

Having thus described the invention, there is claimed as new and desired to be secured by Letters Patent:

1. An opaque alkaline composition for setting hair cold on the human head, said composition essentially consisting of an aqueous carrier, urea, triethanolamine, polyvinyl pyrrolidone and a stable dispersion in the carrier of from 0.1 to 1.0% by weight of an opacifying agent consisting of a primary amide which is the reaction product of ammonia and a saturated higher fatty acid, said amide being selected from the group consisting of behenamide, arachidamide, stearamide, palmitamide and myristamide.
2. An opaque alkaline composition for setting hair cold on the human head, said composition essentially consisting of an aqueous carrier, urea, triethanolamine, polyvinyl pyrrolidone, a stable dispersion in the carrier of from 0.1 to 1.0% by weight of an opacifying agent consisting of a primary amide which is the reaction product of ammonia and a saturated higher fatty acid, said amide being selected from the group consisting of behenamide, arachidamide, stearamide, palmitamide and myristamide, and a solvent for said opacifying agent which solvent consists of nonylphenoxy poly (ethyleneoxy) ethanol including four moles of ethylene oxide.
3. A method of setting hair on the human head comprising applying cold to the hair, an opaque alkaline composition essentially consisting of an aqueous carrier, urea, triethanolamine, polyvinyl pyrrolidone and a stable dispersion in the carrier of from 0.1 to 1.0% by weight of an opacifying agent consisting of a primary amide which is the reaction product of ammonia and a saturated higher fatty acid, said amide being selected from the group consisting of behenamide, arachidamide, stearamide, palmitamide and myristamide.
4. A method of setting hair on the human head comprising applying cold to the hair, an opaque alkaline composition essentially consisting of an aqueous carrier, urea, triethanolamine, polyvinyl pyrrolidone, a stable dispersion in the carrier of from 0.1 to 1.0% by weight of an opacifying agent consisting of a primary amide which is the reaction product of ammonia and a saturated higher fatty acid, said amide being selected from the group consisting of behenamide, arachidamide, stearamide, palmitamide and myristamide, and a solvent for said opacifying agent which solvent consists of nonylphenoxy poly (ethyleneoxy) ethanol including four moles of ethylene oxide.
